UNITED STATES PATENT OFFICE.

HENRY C. EGERTON, OF PASSAIC, NEW JERSEY, ASSIGNOR TO WESTERN ELECTRIC COMPANY, OF NEW YORK, N. Y., A CORPORATION OF ILLINOIS.

TRAIN-DESPATCHER'S TELEPHONE-CIRCUIT.

1,110,913.

Specification of Letters Patent.

Patented Sept. 15, 1914.

Application filed May 17, 1912. Serial No. 697,905.

To all whom it may concern:

Be it known that I, HENRY C. EGERTON, citizen of the United States, residing at Passaic, in the county of Passaic and State 5 of New Jersey, have invented a certain new and useful Improvement in Train-Despachers' Telephone-Circuits, of which the following is a full, clear, concise, and exact description.

10 This invention relates to telephone stations, and the object is to provide apparatus for controlling the use of two kinds of telephone receivers of different characteristics.

According to this invention, one of the 15 receivers which may be of the "loud speaking" type and of high resistance is adapted by means of a switch, when in one position, to be connected in parallel with the secondary winding of an induction coil, this switch 20 in the alternate position connecting the second receiver which may be an ordinary head telephone and of low resistance in series with the secondary winding. A second switch is preferably provided whereby the 25 primary and secondary windings of the induction coil may be either switched out of circuit or placed in operative condition, this switch being capable of use in the same manner whether the loud speaking or head receiver is for the moment connected in circuit by the first mentioned switch.

One advantage of this invention is that the user who, for example, may be a train despatcher has the choice of two receiving 35 instruments, one of which, the loud speaking instrument, may be normally left in service and does not require his presence in the immediate vicinity of the instrument, the other being the highly efficient head receiver, which he can make use of at times when it is desirable that he give close attention to the telephone, and in cases when the 40 quality of transmission over the line is low.

The drawing is a diagram of the circuit 45 and apparatus connections.

The two limbs of the telephone circuit are shown at 1 and 2; a condenser *c* may be included in one limb, as in 1. The transmitter *w* is in a local circuit including battery *d*, 50 primary *p* of an induction coil, and contacts 30 and *g* of a switch *b*, having movable contacts *g* and *i*, and fixed contacts 30, 31 and 32; contacts *g* and *i* are operated by separat-

ing them. This may be done by the use of a foot treadle or in any other manner well known. There are two main line branches *x* and *y*. Branch *x* includes the secondary coil *s*, head telephone *h* and contacts 22 and *f* of a switch *a*. This switch *a* has fixed contacts 20, 21, 22 and 23, and movable contacts *e* and *f* operated by a depressible key which may be locked down and released, in well-known manner. The resistance of the coil of telephone *h* is low which may be about 70 ohms. In the second main line branch *y*, 60 there is included a loud speaking telephone *t* having a high resistance which may be about 600 ohms; it is provided with a trumpet *v* about eighteen inches or two feet in length so that the ear of the listener may 65 be considerably removed from the diaphragm. In branch *y* is also included contacts *e* and 20 of switch *a*. A shunt circuit is formed around secondary coil *s*, and in this shunt there are two contacts in series, 70 one controlled by each switch *a* and *b*. Contacts *e* and 21 are operated by switch *a*, and contacts *i* and 31 by switch *b*. The shunt circuit may be traced from 1 via *y*, *e*, 21, 40, 31, *i*, 41, to *x*. A break point *f*, 22, of switch 80 *a* operates to make and break branch *x*, and a contact *i*, 32 of switch *b*, operates to make and break a by-path of branch *x* either when circuit is made at *f*, 22, or is made at *f*, 23. A branch conductor containing a resistance 85 33 of say, 20 ohms, connects main conductor 2 with contact 23 of switch *a*, and when switch *b* is shifted contact *i* engages contact 32 so that telephone *h* is in a branch from 1 via *s*, *x*, *h*, 22, *f*, 2, and a parallel branch is 90 completed via 2, 33, 23, 32, *i*, 41, and *x*. This decreases the transmission loss, due to connecting telephone *h* in series with coil *s*; it also reduces the side tone in receiver *h*.

It results from the construction shown 95 and described that the despatcher may alternately use the head telephone *h* and the loud speaking telephone *t*, operating the switch *a* to bring one or the other into operation, and he may operate the switch *b* to 100 bring the transmitter and induction coil into use whether the receiver *t* or *h* is for the moment in service. The actuation of switch *b* will connect, in one case, the secondary winding *s* in parallel with the receiver *t* and, 105 in the other case, this winding in series with

the receiver h . In the latter case the receiver h will at the same time be shunted by the resistance 33.

What I claim is:

- 5 1. In a telephone station, line conductors, a transmitter and primary winding of an induction coil, a secondary winding for said induction coil, a high impedance receiver and a low impedance receiver, means for placing either said high impedance or said low impedance receiver in circuit across said line conductors, and means for connecting said secondary winding in series with said low impedance receiver or in parallel with said high impedance receiver.
- 10 2. In a telephone circuit of the character described, line conductors, a local transmitter circuit including a transmitter, battery, and the primary winding of an induction coil, a secondary winding for said induction coil, a high impedance receiver, a low impedance receiver, means for placing either said high impedance or said low impedance receiver in circuit across said line conductors, and means for placing said secondary winding either in series with said low impedance receiver or in parallel with said high impedance receiver and simultaneously closing said local transmitter circuit.
- 15 3. In a telephone circuit of the character described, line conductors, a local transmitter circuit including a transmitter, battery,

and the primary winding of an induction coil, a secondary winding for said induction coil, a high impedance receiver, a low impedance receiver, a switch for placing either said high impedance receiver or said low impedance receiver in circuit across said line conductors, and a second switch for operatively connecting said secondary winding in series with said low impedance receiver or in parallel with said high impedance receiver.

4. In a telephone circuit of the character described, at one station, two parallel main line branches and the local circuit of a telephone transmitter including a primary coil; and in one of said branches a secondary coil, a shunt circuit therefor and a head telephone, in the second branch a loud speaking telephone, in combination with a switch adapted, when operated, to open the first branch, close the second branch and break a shunt circuit around said secondary coil, and a switch adapted, when operated, to close a break point in the first branch, break said shunt circuit at a second point, and close the local circuit.

In witness whereof, I, hereunto subscribe my name this 16th day of May A. D., 1912.

HENRY C. EGERTON.
